UNITED STATES PATENT OFFICE

MILLER REESE HUTCHISON, OF WEST ORANGE, NEW JERSEY, ASSIGNOR, BY MESNE ASSIGNMENTS, TO ACOUSTIC PRODUCTS COMPANY, OF NEW YORK, N. Y., A CORPORATION OF DELAWARE

FLEXED SOUNDING BOARD

Application filed April 1, 1927. Serial No. 180,181.

This invention relates to the faithful reproduction of sound.

The invention has for its particular object the provision of improved means for producing simultaneously musical notes having a wide range of frequencies, together with all the upper harmonics necessary for imparting quality or timber to music whereby the sounds of different musical character may be readily identified.

10 The invention has particular reference to the reproduction of orchestral, band or chord music so that the sounds produced by the different instruments or voices of an ensemble are emitted in the same relative intensities 15 as in the case of the original rendition of the music.

Heretofore in the reproduction of such music by radio loud speakers and the like 20 great difficulty has been experienced in obtaining even an approximation of bass notes. It appears that this difficulty is at least in part the result of impressing upon the apparatus energy corresponding to the higher 25 frequencies of the musical register, and that when the apparatus is responding to such higher frequencies it does not faithfully respond to the energy of low frequency. This difficulty is not apparent when the apparatus 30 is reproducing the bass notes singly as in the case of a bass solo, but develops immediately when the bass notes are to be produced at the same time as the notes of higher range. Consequently it has been found with structures of the prior art that when proper 35 response is obtained in the case of a bass solo, the response with an ensemble of instruments is not faithful and the bass notes are not properly balanced with the higher notes, so 40 that the music is not always reproduced with fidelity.

In attempting to secure the proper balance which is desirable I have discovered that 45 sounding elements of wood operate well under all the conditions obtaining in the reproduction of orchestral, band and choral music. In providing such wooden elements, however, it is important to secure the proper relation between the dimensions of the element and to provide means for flexing the

material about an axis. Accordingly, an important feature of the present invention relates to the provision of sounding elements formed of wood and to the provision of differently flexed elements, each having a predetermined configuration, in combination with means for impressing thereon vibratory energy.

The energy impressing means comprises generally an electromagnetic unit having an actuating element operatively connected to the respective sounding element, and one feature of the invention relates to applying the unit to the sounding board at a point spaced from one edge of the sounding board 55 by a predetermined amount, depending on the thickness and texture of the wood.

Another feature relates to the provision of a plurality of differently flexed sounding elements.

Other objects will appear from the following description taken in connection with the accompanying drawings in which—

Fig. 1 is a sectional elevation of one embodiment of the invention in which the sounding elements are flexed longitudinally taken on the line 1—1 of Fig. 2;

Fig. 2 is a horizontal section taken on the line 2—2 of Fig. 1;

Fig. 3 is a side elevation of a modified form 80 of the invention in which the sounding elements are flexed transversely;

Fig. 4 is a horizontal section taken on the line 4—4 of Fig. 3;

Fig. 5 is a side elevation of a modified embodiment having four sounding elements 85 each flexed transversely;

Fig. 6 is a horizontal section taken on the line 6—6 of Fig. 5;

Fig. 7 is a side elevation of a modified form 90 of the invention having four sounding elements each of which are flexed longitudinally;

Fig. 8 is a horizontal section taken on the line 8—8 of Fig. 7;

Fig. 9 is a side elevation of another modification of the invention having four sounding elements two of which are flexed longitudinally and the other two transversely;

Fig. 10 is a horizontal section taken on the line 10—10 of Fig. 9;

Fig. 11 is a side elevation of another modification of the invention in which two transversely flexed sounding elements of unequal length are arranged at an acute angle with respect to each other;

Fig. 12 is a horizontal section taken on the line 12—12 of Fig. 11.

10 Like reference characters denote like parts in the several figures of the drawing.

In the following description and claims, parts, characteristic features and functions will be identified by specific means for convenience of expression, but they are intended to be as generic in their application to similar parts or equivalent construction as the art will permit.

Referring to Fig. 1 there is provided a base 20 supporting four vertically extending elements 21, 22, 23, 24. Two of the elements designated 21 and 22 respectively, are plain rectangular panels of wood provided merely for the purpose of support. The other two 25 elements 23, 24 are formed of carefully kiln dried wood having all sap carefully removed to avoid fracturing the fiber and having its grain extending vertically. Each sounding element 23, 24 is flexed longitudinally.

30 A top 30 is placed over the upper edges of the elements 21, 22, 23, 24 and is provided on its lower face with a pair of depending brackets 31, 32 each having secured thereto an electromagnetic unit 33, 34 of the loud

35 speaker type for converting undulatory electrical energy into mechanical movement. It is understood that the units 33, 34 are connected by conductors 35, 36 in circuit with a source of undulatory energy such as a radio 40 receiving set, a phonographic pickup device, a public address system or the like. The unit 33 actuates a link 37 serving as an operative connection to the sounding element 23, and the link 37 engages the respective sounding

45 element at a point 38 which is approximately fifteen per cent of the total length of the free portion of the sounding element 23 from one of its edges, the distance depending upon the thickness and texture of the board. Similarly the unit 34 includes a link 39 forming an operative connection with the sounding element 24 and is secured thereto at a point 40 which is also approximately fifteen per cent 50 of the total length of the free portion of the respective sounding element 24. The top 30 is apertured as at 41 and the bottom is apertured as at 42 for the emission of sound waves from the interior of the device.

60 In operation, undulatory electrical energy is transmitted over conductors 35, 36 to the units 33, 34 and causes longitudinal movement of the respective links 37, 38. This movement is applied to the sounding elements 23, 24 causing them to vibrate accordingly.

65 It is a characteristic of a longitudinally

flexed sounding element that it responds especially well to low pitched notes. It is in effect a series of long parallel wood fibers extending longitudinally and responding to relatively low natural frequencies. Furthermore, by applying the vibratory energy near one end of the structure the center portion is oscillated to a greater degree producing vibrations of relatively large amplitude in the surrounding natural medium without excessive clearance between the armature and poles of the actuating unit.

70 In the modified form of the invention shown in Figs. 3 and 4, four vertically extending elements 51, 52, 53 and 54 are provided. The elements 51 and 52 correspond to the plane rectangular panels of wood shown as at 21, 22 of Fig. 2 and are provided merely for the purpose of support. The other two elements 53, 54 are formed of carefully kiln dried wood having its grain extending vertically with respect to Fig. 3 and flexed transversely. An electromagnetic unit 55 is provided for the vibratory element 53 being secured thereto by a link 56 engaging the sounding element at a point which is approximately 15% of the total length of the free portion of the sounding element from one of its edges. A second electromagnetic unit 57 having a link 58 is similarly connected to the 85 opposed sounding element 54.

90 In the operation of the embodiment shown in Figs. 3 and 4 electrical energy modulated in accordance with a signal current of complex wave form is applied to the units 55, 57 and causes longitudinal movement of the respective links 56, 58. This movement is communicated to the sounding elements 53, 54 causing them to vibrate accordingly. It is a characteristic of sounding elements of this 100 form to respond to notes of relatively higher pitch than those to which the longitudinally flexed sounding elements of the embodiment of Figs. 1 and 2 respond.

105 The embodiment of Figs. 5 and 6 is similar to that of Figs. 3 and 4 except that four transversely flexed sounding boards 61, 62, 63 and 64 are provided. Each sounding element is provided with an electromagnetic unit such as 65 having a link 66 operatively connected to the respective sounding element at a point which is approximately 15% of the total length of the free portion of the sounding element from one of its edges.

110 In operation electrical undulatory energy is applied to the four electromagnetic units 65 simultaneously and each causes vibration of the associated sounding elements in accordance with the signal wave. A larger volume of sound emitted in all directions 125 with substantially equal intensity is thus obtained.

120 The embodiment of Figs. 7 and 8 is similar to that of Figs. 1 and 2 except four longitudinally flexed sounding boards 71, 72, 73 and 125

74 are provided. Each is formed as in the embodiment of Figs. 1 and 2 and is provided with an electromagnetic unit such as 75 having a link 76 operatively connected to the 5 respective sounding element at a point which is approximately 15% of the total length of the free portion of the respective sounding element from one of its edges.

In operation electrical undulatory energy 10 is applied to the four electromagnetic units 75 simultaneously and each causes vibration of the associated sounding element in accordance with the signal wave. A larger volume of sound, of low pitch is thus transmitted 15 effectively in all directions.

In the modified form of the invention shown in Figs. 9 and 10 four vertically extending elements 81, 82, 83 and 84 are provided. The elements 81, 82 are similar in 20 construction to the sounding elements 53, 54 of Figs. 3 and 4 and are flexed transversely. The other two elements 83, 84 are similar in construction to the elements 73, 74 and are flexed longitudinally.

25 Each of the four sounding elements 81, 82, 83 and 84 is provided with an electromagnetic unit such as 85 having a link 86 operatively connected to the respective sounding element at a point which is approximately 15% of the 20 total length of the free portion of the respective sounding element from one of its edges.

In operation electrical undulatory energy 30 is applied to the four electromagnetic units 85 simultaneously and each causes vibration of the associated sounding element in accordance with the signal wave. A larger volume of sound, of low pitch is thus transmitted effectively in all directions.

In the modified form of the invention 40 shown in Figs. 11 and 12 two elements 91, 92, preferably of relatively different lengths are positioned at an acute angle with respect to one another. Each is provided with an electromagnetic unit such as 93, 93, each unit 45 having a link such as 94 extending therefrom to the respective sounding element at a point which is approximately 15% of the total length of the free portion of the respective sounding element from one of its edges. In the drawing the sounding elements 91, 92 50 are shown as being flexed transversely, but it is understood that they may be flexed longitudinally as disclosed in Figs. 7 and 8, or one 55 may be flexed transversely and the other flexed longitudinally as in the combination shown in Figs. 9 and 10.

In the operation of the modified form of the invention of Figs. 11 and 12 electrical undulatory energy is applied to the two electromagnetic units 93 simultaneously and each 60 causes vibration of the associated sounding element in accordance with the signal wave. Musical sound of improved quality is thus 65 produced.

Thus it will be seen that I have provided a sound propagator formed of a cellular material, flexed in varying combinations to produce music of improved quality. The cellular texture of the material, and the flexure of 70 the material greatly improves the quality of the sound. By providing sounding elements fixed in different planes brilliant as well as mellow sounds are effectively produced thus increasing the attractiveness of the music to a 75 great extent.

The invention upon which this application is based is broader than the specific embodiment shown and described for the purpose of illustrating at least one of the ways in which 80 it may be employed. The scope of the invention is therefore to be understood as not being limited by the present specific description. I intend no limitations other than those imposed by the claims.

85 What is claimed is:

1. A sound producer comprising a plurality of sounding boards flexed transversely, other sounding boards flexed longitudinally, and means for vibrating all of said boards 90 simultaneously.

2. A sound propagator comprising a plurality of differently flexed sounding boards forming a hollow chamber and a corresponding plurality of operating units for actuating 95 said boards respectively.

3. A sound propagator comprising a plurality of sounding boards flexed transversely, other sounding boards flexed longitudinally, said boards forming collectively a hollow chamber, and means for actuating said boards simultaneously.

Signed at New York, in the county of New York and State of New York, this 30th day of March, A. D. 1927.
